MAGNETIC CORE

Josef Kreuzer and Otto Ascher, Graz, Austria, assignors to "Elin" Aktiengesellschaft für Elektrische Industrie, Vienna, Austria, a joint-stock corporation of Austria

Filed Sept. 18, 1956, Ser. No. 610,524

Claims priority, application Austria Sept. 20, 1955
2 Claims. (Cl. 336—5)

This invention relates to magnetic core structures for use in electrical induction apparatus such as transformers and reactors.

The necessity for installing in one transformer unit more and more power without exceeding the dimensional limits imposed by railroad transportation led, in single-phase transformers, from the two-leg-core to the four-leg-core and, in three-phase transformers, from the three-leg-core to the five-leg-core. The outer legs may then also be wound. In such cases, the circumstance, that the outer legs have rectangular cross sections, is a considerable disadvantage, because the coils placed on the outer legs must be wound oval, and therefore possess only relatively small short-circuit strength.

It is an object of this invention to provide a structure for a transformer or reactor core having n main legs ($n \geq 2$) and two outer legs, the latter having an approximately round cross section with a diameter smaller than the diameter of a main leg, and connecting yokes the height of which is considerably reduced.

It is a further object of this invention to provide a transformer or reactor core the iron losses of which are greatly diminished owing to its structure guarantying clean lines for the magnetic flux.

Other objects and advantages of the invention will be apparent from the following description of a preferred embodiment thereof, reference being made to the accompanying drawings, in which:

FIG. 1 is a partial front elevation of a magnetic core according to this invention with four legs;

FIG. 2 is a transverse section through the legs of a core according to FIG. 1;

FIG. 3 is one half of a section through a main leg (section α in FIG. 1).

FIG. 4 is one half of a section through a main yoke (section β in FIG. 1);

FIG. 5 is one half of a section through an outer yoke (section γ in FIG. 1) and

FIG. 6 is one half of a section through an outer leg (section δ in FIG. 1).

Although not wishing to confine this invention to magnetic cores stacked of cold-rolled sheets, having therefore a greater permeability and lesser watt losses per unit volume when the flow of flux is through the steel in the direction of rolling than when it is through the core in other direction, it is, however, assumed for purposes of illustration that the core be built up of a high grade steel, and is extensively subdivided by cooling ducts running parallel to or at right angles with the planes of the laminae.

As is seen from FIG. 2 the magnetic core consists of ($n+2$)-leg core, where $n=2$ the layers of which have everywhere the same height $d_1=c_1=a_1=b_1$. On both sides of the n main legs 1 and 2 there are added further stacks of sheets 9 and 10 each having a height of layer a_2 . The cross section of the main legs is completed in this approximately a full circle. The stacks are closed to a full two-leg magnetic circuit by yokes 6, 7, and 8 of a height of layer b_2 (in which $b_2=a_2$). The diameter of the resulting cross section of a main leg is indicated in FIG. 2, by D , the diameter of the outer legs, 3 and 4 by d .

2

Between the layers with the height b_1 and the layers with the height b_2 a cooling duct 11 is provided.

In FIG. 3, the breadth of sheets forming one bundle of laminae of a main leg of the ($n+2$)-leg core is indicated by

$$\frac{Ax}{2}$$

that of the further stacks of sheets 9 and 10 of a main leg of the core by

$$\frac{Ay}{2}$$

The second half of the sectional area may be thought to be specularly symmetrical.

Likewise, in FIG. 4, 5 and 6 the breadth of sheets forming one bundle of laminae of the main yoke 6, the outer yokes 7 and 8 and the outer leg belonging to the ($n+2$)-leg core are indicated by

$$\frac{Bx}{2}, \frac{Cx}{2} \text{ and } \frac{Dx}{2}$$

the breadth of sheets forming one bundle of further laminae of the yoke 6 connecting the main legs of the core is indicated by

$$\frac{By}{2}$$

The diameter of the main legs and the outer legs is indicated again by D and d . As is to be seen from the FIGURES 4 and 5, also the main yoke and the outer yoke possess cooling ducts running at right angles to the plane of lamination. The breadth of all sheets lying in series in the direction of the magnetic flux is the same, that is, according to reference letters of FIGURES 3-6

$$\frac{Bx}{2} = \frac{Cx}{2} = \frac{Dx}{2} = \frac{Ax}{4} \text{ and } \frac{Ay}{2} = \frac{By}{2}$$

Therefore, also, the staggering of the bundle of laminations lying in series in the direction of the magnetic flux is the same and the resulting core possesses simple and clear lines for the magnetic flux also in its corners and equal induction in all bundles of laminations of the legs and of the yokes. The advantages connected with these features of the magnetic core according to this invention are obvious especially if high grade steel is used. The hollows which occur in the outer legs when the above postulate

$$\frac{Bx}{2} = \frac{Cx}{2} = \frac{Dx}{2} = \frac{Ax}{4}$$

is fulfilled may be used for cooling. The maximum height connecting the yoke of the main legs of the core amounts to half the diameter of a main leg

$$\left(\frac{Bx_{\max}}{2} = \frac{Cx_{\max}}{2} = \frac{D}{4} \right)$$

By dividing the total core in suitable manner into the ($n+2$)-leg core and the two-leg cores there is attained that also

$$\frac{By_{\max}}{2} = \frac{Ay_{\max}}{2} = \frac{D}{4}$$

Because in such a manner the yoke sheets of the n -leg core get approximately the double height compared with yoke sheets in corresponding layers of a usual ($n+2$)-leg core, there is no need to increase the height in order to get sufficient pressure surface. Therefore equal induction exists also in the outer zones of the yoke and there will not be originated transverse fluxes increasing the losses, particularly if cold-rolled sheets are employed.

Obviously, the afore-mentioned equation of condition

for exact equal induction in each bundle of laminae is not to be observed rigorously, but there may be deviation from it by reducing the number of steps of the yokes (of the main yokes and of the outer yokes) and of the outer legs to about one half, as it is shown in the figures. In such a case the height of sheets for one bundle of laminae of a yoke or an outer leg may amount to the average of the height of the two main leg steps lying in series for the magnetic flux.

In FIG. 1 of the accompanying drawing the magnetic core according to this invention is shown as an overlapped laminated one. The yokes and legs may also be butt-jointed. The use of the mitered-joint is also possible and advantageous especially if the core is stacked of high grade steel sheets.

The advantages of a core according to this invention are essentially as follows. It is an easily and therefore inexpensively manufacturable magnetic core with favorable guidance for the magnetic flux. The main legs and also the outer legs possess circular cross section and the height of the yokes is reduced to half the main leg diameter. Apart from the mitered-joint modification all sheets show rectangular shape. They may therefore be manufactured only by cutting and need no stamping methods leaving waste material and causing burrs. Each bundle of laminae of the legs and of the yokes has the same induction and undergoes therefore also equal heating. The guidance of the magnetic flux is clear also in the corners and branching points for the magnetic lines and there is no cause for additional iron-losses. The advantages for the yoke pressure are mentioned above. At last, as the sheets are all stacked in parallel, no bending or buckling is required which would cause considerable deterioration of the iron-losses per unit volume especially with cold-rolled sheets.

What we claim as new and desire to secure by Letters Patent is:

1. A laminated magnetic core comprising at least two outer legs, two main legs and yoke portions closing the magnetic circuits between said outer and main legs respectively, said outer legs being comprised of stacks of laminae forming an approximately circular cross-section of a diameter smaller than the diameter of said main legs, said main legs each being comprised of a central stack of laminae having the same height of layer as the

outer legs and being flanked on opposite sides from a common plane through the center lines of the main and outer legs by further stacks of laminae completing the cross-section of the main legs to approximately a full circle, said central stacks of laminae of the main legs and the stacks of laminae of the outer legs being combined by said yoke portions to first closed magnetic circuits, the stacks of laminae flanking the main legs being closed by further yoke portions to further magnetic circuits lying parallel to said first magnetic circuits, respectively, the laminae of all stacks of the legs and the yoke portions lying in series for the magnetic flux lines having the same breadth.

2. A laminated magnetic core comprising at least two outer legs, two main legs and yoke portions closing the magnetic circuits between said main legs and said outer legs respectively, said outer legs being comprised of stacks of laminae forming an approximately circular cross-section of a diameter smaller than the diameter of said main legs and having centrally situated hollows, the main legs being comprised of central stacks of laminae having the same height of layer as the outer legs and being flanked on opposite sides from a common plane through the center lines of the main and outer legs by further stacks of laminae completing the cross-section of the main legs to approximately a full circle, said central stacks of laminae of the main legs and said stacks of laminae of the outer legs respectively, being combined by yoke portions to closed magnetic circuits, the stacks of laminae flanking the main legs being closed by further yoke portions to further magnetic circuits lying parallel to the first magnetic circuits respectively, the laminae of all stacks of the legs and the yoke portions lying in series for the magnetic flux lines having the same breadth.
